(57) **CLAIM**

The ornamental design for a bore swabbing tool, as shown and described herein.

DESCRIPTION

The invention described and claimed herein may be manufactured, used, and licensed by or for the U.S. Government for U.S. Government purposes.

FIG. 1 is a rearward looking perspective view of a bore swabbing tool of our new design;

FIG. 2 is a forward looking perspective view thereof;

FIG. 3 is a side view thereof; wherein, the view 180 degrees opposed thereto is a mirror image thereof, except that there is no elongated break in the rear threaded section;

FIG. 4 is a front elevation view thereof; and,

FIG. 5 is a rear elevation view thereof.
